UNITED STATES PATENT OFFICE.

OTTO HEER, OF DÜSSELDORF, GERMANY.

HYDRAULIC DRAW-BENCH.

SPECIFICATION forming part of Letters Patent No. 781,202, dated January 31, 1905.

Application filed October 8, 1903. Serial No. 176,301.

To all whom it may concern:

Be it known that I, OTTO HEER, engineer, a citizen of the Swiss Confederation, residing at No. 45 Graf Adolf strasse, in the city of 5 Düsseldorf, Kingdom of Prussia, German Empire, have invented certain new and useful Improvements in Hydraulic Draw-Benches, of which the following is a specification.

The object of this invention is a hydraulic wire-drawing frame of a special construction whose power expended can be adapted in every single case by degrees and within wide limits to the power required without altering the pressure of the driving medium by the arrangement that several driving-cylinders 15 working simultaneously or separately and independently can effect the drawing.

On the drawings this drawing-frame is shown in Figure 1 in a longitudinal section 20 on the line $v v$ of Fig. 3; in Fig. 2 in a longitudinal section on the line $w w$ of Fig. 3. Fig. 3 is a plan or top view; Fig. 4, a cross-section on the line $x x$; Fig. 5, a cross-section on the line $y y$, the side cylinders working separately; Fig. 6, a cross-section on line $z z$, showing the three cylinders working together.

Similar letters refer to similar parts throughout the several views.

30 The apparatus is constructed with three driving-cylinders $a b c$, not connected with each other, fixed alongside each other on the same level, parallel, and in a horizontal position. Of the rams $d e f$ of these cylinders 35 only the outside ones, $d f$, are provided on their outer or front ends with slide-blocks $g h$, which travel along slides $i k$ in a line with the axis of their driving-cylinder. The ram e of the middle cylinder b (which is prefer- 40 ably of a larger diameter than the others) is provided with no special guide. The outer end of the ram e of the middle cylinder b is of a conical shape corresponding with a conical bore in the cross-head l , intended to receive 45 this end. This cross-head is of the same width as the slide-blocks of the side plungers. Its two ends are bifurcated, and the two prongs of this fork catch over the head-pieces $g' h'$ in the center of the upper surface of the slide

blocks $g h$, the breadth of each of which is 50 equal to the space between the two prongs of the bifurcated ends of the cross-head through which they pass. By means of screws $m n$, screwed into corresponding borings in the prongs and into the head-pieces $g' h'$ between 55 the prongs, a firm union is effected between the cross-head l and the two slide-blocks $g h$.

Each of the three cylinders is provided with a suitable valve arrangement t , by means of which the interior can be put in communication with the supply-pipe u of the high-pressure water or the outlet-pipe u' or shut off from either. For work which does not require a large amount of power each of the two side cylinders is used separately, the dies p 65 required being preferably affixed to the front flange of the cylinders and the internal dies p' , required for drawing piping and the like, affixed to the back of the cylinders. The forward movement of the materials which are 70 being drawn and which are secured to the heads $g' h'$ of the slide-blocks $g h$ by means of clamps s is caused by the rams $d f$, which are subjected to the force of the high-pressure water entering the cylinders, while the return 75 motion of all the parts is effected on either side by means of a weight r , which is raised by means of the loose pulley q of a pulley-block, when the respective slide-block moves forward and sinks down on the pressure-water being let off. If the power of one of the outside cylinders is insufficient for a given piece of work, the two are combined by means 80 of the cross-head l , clamps s being withdrawn and bolts $m n$ inserted instead, and the piece 85 of work is secured to a clamp forming the head of the bolt o , secured to the cross-head l . The central ram is not moved in this case. It is only brought into action should the power 90 of the outside cylinders be insufficient for the work required. Under certain circumstances it may, however, be used by itself, in which case the rams of the two outside cylinders which remain inactive and which are not rigidly connected with their sliding blocks are 95 uncoupled therefrom and the blocks move forward independently of them.

In some cases more than three cylinders

may be used, and thus a more complex combination regarding the adaptation to the power expended each time be attained.

What I claim as my invention, and desire to secure by Letters Patent of the United States, is—

1. In combination with three parallel fluid-actuated cylinders and their plungers, a cross-head adapted to be engaged by the middle plunger, devices interposed between the two outer plungers and the said cross-head in order that the said plungers and cross-head may move together and means moving with the said cross-head for holding the rods or tubes to be operated on, the said parts permitting the two outer plungers to work either with or without the middle plunger substantially as set forth.

2. A pair of fluid-actuated cylinders and their plungers, adapted to work together, in combination with devices actuated by said plungers, a third fluid-actuated cylinder, its plunger and means actuated at will by the latter and connecting said devices in order that the three may coöperate, and said means adapted to carry a clamp for the article to be operated on, substantially as set forth.

3. A pair of fluid-actuated cylinders and their plungers, in combination with sliding blocks adapted to be engaged by the said plungers, means connecting the said blocks to each other in order that they may work together, a third fluid-operated cylinder and its plunger, the latter plunger engaging and actuating at will said connecting means in order that the three may coöperate substantially as set forth.

4. Three parallel fluid-actuated cylinders and their plungers, devices engaged by the outer plungers, in combination with means for connecting said devices, said means being also adapted to be engaged by the middle one at will, and automatic means for replacing each of the outer plungers, the outer plungers being adapted to act independently of the middle one when the latter is not thus engaged and the middle plunger being adapted to act alone substantially as set forth.

5. Three parallel fluid-actuated cylinders and their plungers, in combination with a pair of guides, a pair of slide-blocks moving in said guides and adapted to be engaged by the two outer plungers and a cross-head connected to the said blocks and adapted to be engaged by the middle plunger, the cross-head being separable at will from the middle plunger or the said pair of blocks, substantially as set forth.

6. Three parallel fluid-actuated cylinders and their plungers, in combination with sliding blocks adapted to engage the two outer plungers, weights connected to the said blocks for withdrawing the same automatically, a pair of fixed guides for said blocks, a cross-head connected to the said blocks and adapted to be engaged by the said middle plunger and

rod-holding means adapted to be applied to the said cross-head at will substantially as set forth.

7. Three reciprocating plungers, in combination with blocks engaged by and moving with the two outer plungers, a cross-head adapted to be engaged by the middle plunger and also by said blocks, and rod-holding means constructed to be attached to said cross-head, the construction and combination of the said parts permitting the middle plunger to be used alone, or the two outer plungers to be used without it or all three of the plungers to be used together substantially as set forth.

8. A pair of reciprocating plungers in combination with a pair of sliding blocks adapted to detachably engage them respectively, and to receive rod-holding means, guides for the said blocks and means for connecting the said blocks together, in order that either plunger may be used alone or both plungers in coöperation, the said connecting means being also provided with a rod-holding device, substantially as set forth.

9. A pair of reciprocating plungers, in combination with a pair of sliding blocks adapted to detachably engage them respectively, and to receive rod-holding means movable therewith, guides for the said blocks, means for retracting the said blocks automatically and independently and means for connecting the said blocks together in order that either plunger may be used alone or both plungers may be used in coöperation, the said connecting means being provided with a rod-holding device, substantially as set forth.

10. A pair of reciprocating plungers, in combination with a pair of sliding blocks adapted to detachably engage them respectively, and to receive rod-holding means movable therewith, guides for the said blocks, a cross-head connecting said blocks together, a third reciprocating plunger adapted to detachably engage the said cross-head for coöperating with the other two plungers and means for retracting the said blocks and cross-head automatically, the said cross-head being also provided with a rod-holding device, substantially as set forth.

11. Two plungers and means to actuate the same, in combination with blocks adapted to be engaged by said plungers and constructed each to receive a clamp and a cross-head constructed to connect said blocks and also to receive a clamp, whereby the two plungers may be used separately or together.

12. Two plungers and means to actuate the same in combination with devices engaged and moved by said plungers and means connecting said devices, the devices thus engaged and also the said connecting means being adapted to receive and carry work-holding attachments, in order that the said plungers may be used separately or together.

13. Three plungers and means for actuating them, in combination with devices engaged by two of the said plungers and adapted to receive clamps at will, means connecting the said devices together and also adapted to receive a clamp and engage the third plunger, whereby the three plungers may be used separately or all together, or two of them without the third, as desired.
14. Three plungers and means for actuating them, in combination with blocks engaged by two of the said plungers respectively moving with the same and adapted to carry clamps,

and a cross-head, connecting said blocks at will, engaging the third plunger and also adapted to carry a clamp in order that the three plungers may be used separately or together or two of them without the third if preferred, substantially as set forth.

In witness whereof I have hereunto set my hand in presence of two witnesses.

OTTO HEER.
